UNITED STATES PATENT OFFICE.

JACOB P. SAWATZKY AND ABRAHAM B. GERBRAND, OF HUTCHINSON, KANSAS.

HARNESS-BUCKLE.

1,126,876.

Specification of Letters Patent. Patented Feb. 2, 1915.

Application filed May 6, 1913. Serial No. 765,861.

To all whom it may concern:

Be it known that we, JACOB P. SAWATZKY and ABRAHAM B. GERBRAND, citizens of the United States, residing at Hutchinson, in the county of Reno and State of Kansas, have invented certain new and useful Improvements in Harness-Buckles, of which the following is a specification.

Our invention relates to buckles and, particularly to buckles for harness.

The primary object of the invention is the provision of a simple and effective buckle wherein there shall be no part which will project from the buckle and thereby be liable to catch in other portions of the harness or the horse trappings.

A further object is to provide a buckle wherein the tongue of the buckle is housed when the buckle is in use and wherein the tongue is locked against accidental opening, thus preventing the buckle from catching upon the fly net of the harness or catching in the rings through which the lines pass.

Other objects will appear in the course of the following description.

Our invention is illustrated in the accompanying drawings wherein:

Figure 1 is a perspective view of a buckle constructed in accordance with our invention and shown as connected to the straps joined by the buckle. Fig. 2 is a perspective view of the buckle in open position.

Fig. 3 is a longitudinal section of the buckle when in use.

Corresponding and like parts are referred to in the following description and indicated in all the views of the accompanying drawings by the same reference characters.

Referring to these figures it will be seen that the buckle is formed of two sections hingedly connected to each other, one of said sections carrying a hinged tongue and the other a tongue locking device. The tongue carrying section consists of an approximately rectangular frame 2 having a relatively straight cross bar 3 at one end whereby one part of the line or other portion of the harness may be attached to the buckle and at the other end a rounded cross bar 4. Intermediate between the two cross bars but nearer to the first cross bar is a

cross bar 5. Preferably the cross bar 5 is disposed slightly below the general level of the frame.

Hingedly mounted on the curved cross bar 4 is a hook-shaped tongue 6 bent intermediate its ends to form two parallel legs, one of said legs being longer than the other, the short leg being enlarged at its end and embracing the curved cross bar 4. The hook-shaped tongue may be held in proper position upon the curved cross bar in any suitable manner and be prevented from lateral displacement but as illustrated the tongue is held in place upon the cross bar 65 by a clip comprising a strip of sheet metal designated 7. The extremities of this strip are turned over the side bars of the frame as at 8 and on each side of the tongue the strip is formed with ears 9 which are bent over 70 and around the cross bar 4. The tongue is thus held in position but prevented from lateral displacement. It will be seen that the tongue can rotate nearly through a complete circle. The other section of the buckle 75 is best illustrated in Fig. 2 and consists of a sheet metal plate 10 and a rectangular frame 11. The extremity of the plate is angularly bent upwardly, as at 12, as is the cross bar 13. The plate is held to the frame by providing the side edges 6 of the plate with ears which are turned over upon the frame 11. Toward the forward end of the plate, the plate is slotted as at 13, this slot extending into the upwardly turned 85 portion of the plate. At its rear end the plate is reduced in width and curved to form a bead 14 which surrounds the cross bar 5 thereby hinging the plate to the cross bar.

Referring to these figures it will be seen that the plate 10 is a latch 15. This latch is adapted to be shifted over the slot 13 or shifted to one side to disclose the slot. The latch is also made of sheet metal and formed with 95 an ear which is rolled over to form a finger piece 16 whereby the latch may be shifted.

While we have described in detail the exact construction of our improved buckle, it will of course be understood that the details 100 of the construction as illustrated and described are not absolutely essential to the

proper operation of the device and that the buckle may be constructed in many other ways within the scope of the appended claims without departing from the spirit of the invention.

In use, the frame 2 is connected by means of the cross bar 3 to a strap A. The tongue 6 is adapted to be passed through a perforation in the strap B which is to be joined 10 with the strap A and then the two sections of the buckle are brought together and the tongue is inserted in the slot 13 and pressed inward beyond the plate 10. After the tongue is inserted, the latch 15 is shifted so 15 as to be interposed between the tongue and the slot holding the tongue securely in place and preventing any opening of the tongue until the latch is shifted back to disclose the slot whereupon the tongue may be withdrawn. The strap B is preferably passed 20 over the bead 14 and between the frame 2 and the frame 11 as illustrated in Fig. 3.

It will be obvious that with a buckle constructed as above described, it will be impossible to withdraw the strap from engagement with the buckle unless the tongue be unlocked, and further it is obvious that the extremity of the tongue is housed between the strap B and the plate 10 in such 30 position that it can not engage with any other part of the harness and can not catch or hold on anything. Furthermore it will be seen that strain coming upon the strap B will be transmitted to the frame 2 and to 35 the latch 15. Further it will be apparent that even if the latch be accidentally loosened, the strain upon the strap B will not open the buckle, as the strain will come upon the hook-shaped tongue at the bend thereof 40 and not upon the free extremity of the tongue as in ordinary buckles.

What we claim is:

1. A buckle of the character described 45 consisting of two sections, the rear end of one section being hinged to the other section adjacent its rear end whereby to permit the sections to be opened to admit a strap, a tongue hinged to one section and rotatable into position to engage over the free end of 50 the other section, and a keeper mounted upon last named section and adapted to engage the end of the tongue to lock the tongue to said last named section.

2. A buckle of the character described 55 consisting of two sections, the rear end of one section being hinged to the other section adjacent its rear end whereby to permit the two sections to be opened and thereby admit a strap, a curved tongue hinged to one section and rotatable into position to engage over the free end of the other section, said last named section having adjacent its free end a slot to receive the bill of the tongue, and a keeper mounted upon said last named 60 section for movement with this section and

shiftable across the slot to lock the tongue in engagement with the last named section.

3. A buckle of the character described including two sections hinged to each other, one of said sections having the form of an open frame, the other of said sections including a plate turned at its free end toward the other section and having a longitudinal slot extending partly into the upwardly turned portion of the plate, a U-shaped tongue hinged to the free end of the first named section and adapted to be turned to bring its bill into the slot of the second section, and a keeper pivoted to the inner face of the plate and shiftable into position 80 across the slot and beneath the bill of the tongue to thereby lock the tongue in engagement with the section.

4. A buckle of the character described including two sections hinged to each other, 85 one of said sections comprising an open approximately rectangular frame, the other section comprising a plate hinged at one end to the first named section and the free end being upwardly bent, the plate being 90 formed with a slot extending partly into the upwardly bent portion of the plate, a frame attached to the margins of said plate and a U-shaped tongue hinged to the cross bar at the free end of the first named section and 95 rotatable into position around the free end of the second section whereby to insert the bill of the tongue into the slot in the second section, and a keeper pivoted upon the inner face of the plate and shiftable into position 100 between the plate and the bill and over said slot.

5. A buckle of the character described including two sections, one of said sections having the form of an approximately rectangular frame providing two end cross bars and an intermediate cross bar, a clip disposed upon the free end of the section, a tongue pivoted upon the cross bar at the free end of the section and held from lateral 110 displacement by the clip, a section formed of a plate of sheet metal, one end of which is rolled into a bead and engaged with the intermediate cross bar of the first section, the free end of said plate being inclined 115 toward the first section and extending beyond the same, said plate being formed with a longitudinal slot extending partly into the upwardly turned portion of the plate, a frame attached to the side edges of the plate, 120 a tongue hinged to the cross bar at the free end of the first-named section, said tongue being bent upon itself and having a bill extending beyond the base portion of the tongue, a keeper pivoted upon the inner face 125 of the plate and shiftable across the slot therein, and a strap attached to one of the cross bars of the first named section.

6. A buckle of the character described 130 consisting of two sections, one of said sec-

tions being formed with a cross bar to which a strap is adapted to be connected and with a second cross bar adjacent thereto, the other of said sections having hinged engagement at its rear end with said second named cross bar, a tongue hinged to one of said sections and rotatable into position over the free end of the other section, and a keeper mounted upon the last named section adjacent its free end and shiftable into posi-

tion to lock the tongue in engagement with the keeper carrying section.

In testimony whereof we affix our signatures in presence of two witnesses.
